Primary Examiner — John Windmuller*Assistant Examiner* — Benjamin M Weeks(74) *Attorney, Agent, or Firm* — Myers Andras LLP;
Joseph C. Andras(57) **CLAIM**

The ornamental design for a tire carrier, as shown and described.

DESCRIPTION

FIG. 1 is a left front perspective view of the tire carrier according to my design;

FIG. 2 is a right front perspective view of the tire carrier;

FIG. 3 is a front elevational view of the tire carrier;

FIG. 4 is a back elevational view of the tire carrier;

FIG. 5 is a top view of the tire carrier;

FIG. 6 is a bottom view of the tire carrier;

FIG. 7 is a left view of the tire carrier; and,

FIG. 8 is a right view of the tire carrier.

The surface shading is provided to show the contour of all surfaces, i.e. the shape of the design. It is not intended to represent any particular material or visible surface pattern.
